Allen & Allen

ATTORNEY.

UNITED STATES PATENT OFFICE

CLIFFORD TRAUT, OF NEWPORT, KENTUCKY, ASSIGNOR TO THE HIGGIN MANUFACTURING COMPANY, OF NEWPORT, KENTUCKY, A CORPORATION OF WEST VIRGINIA

TENSION BAR AND GUIDE FOR ROLL SCREENS

Application filed March 17, 1928. Serial No. 262,417.

While my invention is adaptable for holding down the flexible elements of various rolled closures for windows and the like, such as curtains and shades, it is of particular importance in its application to rolled screen closures. These comprise generally a housing at the top of the window opening containing the well known spring roller upon which the screen is wound, and supports therefor. The screen itself is preferably specially woven of the correct width and there are provided guides into which the edges of the screen may enter so as to effect a complete insect-proof closure for the entire window space when the screen is withdrawn from the housing by means of a tension bar.

It is an object of my invention to provide a construction of guides and tension bar which is cheaply and easily made through the utilization of such agencies as are possessed by the manufacturer of metal-framed screens. It is an object of my invention to provide a construction which is readily attached to a window opening in cooperation with the housing containing the roll. Further it is my object to design the guides and bars so that, while the screen can be held at any desired position along the guides, or fully closed without a latch, it nevertheless is easily moved, and the tension bar is prevented from acting unevenly as by riding higher along the guides at one side than the other, and all of this in a construction which is very inexpensive. These and other objects of my invention will be apparent to one skilled in the art upon reading these specifications.

In the drawings:

Figure 1 is a vertical view of my tension bar assembly showing the screen and the guides in section.

Figure 2 is a section through the metallic member forming the body of my tension bar.

Figure 3 shows the screen fastening member.

Figure 4 is a section through the middle of my tension bar.

Figure 5 is a view from the front of an end thereof.

Figure 6 is a view from the rear of an end thereof.

Figure 7 shows one of my guides.

The screen guides, as will be seen in Figures 1 and 7 are formed of two pieces of sheet metal 1 and 2 on each of which there is a turned over edge portion 3 and 4, the purpose of which is to provide a thickened and reinforced edging for the slot 5. The metal piece 2 is bent in a general U shape to provide the guideway 6. This is of rectangular cross section inside and out, and furnishes a channel in which one member of the tension bar slides as will be fully described. The pieces 1 and 2 are fastened together along their flat portions by rivets 7 as shown in Figure 7, or by spot welding, or may be one piece of metal folded on itself. The flat portion may also where desired be perforated for the passage of screws or bolts to fasten it to the window frame. The shape of the guides will be understood by reference to Figure 7; and it will be clear that the shape of the members is such as to provide a flat portion for attachment, a channel or guideway and a slot. The portions 3 and 4 approach each other closely, since this slot, while wide enough to allow free passage for the edge of the screen, and the easy working of the tension bar, must be narrow enough to cooperate with the screen-edge in forming an insect-proof closure.

My tension bar comprises a main or body member 8 of sheet metal bent upon itself as is shown in Figure 2. The front of the bar will have the appearance of a solid bar shown in Figure 5; but from the rear it will be seen that the metal forms a rectangular D section (9 in Figure 2) of less than the full width of the bar, and that one arm of the D is bent over so as to lie parallel with the face of the bar and is preferably fastened thereto for strength, as by spot-welding. The projecting end of the metal beyond the D is given a right-angled bend as shown at 11, and the edge thereof is bent over as at 12. This construction forms a channel 13, within which the screen is fastened; and it will be observed that the bent-over section 12 forms a shoulder within the said channel.

To fasten my screen, I make use of a member of spring sheet-metal shaped as shown in Figure 3. There is a screen engaging edge 14, a shoulder 15, a U shaped portion 16, and a flat portion 17 adapted to lie above the D. The method of attachment of the screen will be understood from Figure 4 where the screen cloth 18 is shown as entering the channel 13. The screen fastening 5 clamp of spring metal is inserted over the screen cloth in the channel 13. The springiness of the metal causes the clamp to expand in the channel, pinching the screen against the shoulder at 12, and holding it fast to the channel bar. It will be obvious that other means than the specific clamp which I have 10 illustrated and described may be used if desired to hold the screen in the channel.

Having now described my guides and the tension bar body together with the preferred method of fastening the screen thereto, I will now describe the means whereby the movement of the tension bar is directed and controlled along the guides. Broadly these 20 means comprise a member adapted to ride in the guideway and of sufficient length so that the tension bar may be held throughout its movement in fixed angular relationship to the guides, a narrow member passing 25 through the slot and adapted to join the first member to the tension bar, and frictional means restricting the movement of the first mentioned member in the guideway. While these means may, if desired, be constructed 30 integrally with the tension bar, I prefer to embody them in a separate metallic structure which is shown clearly in Figure 5. This structure is formed of a single piece of sheet metal cut and bent so as to form a back piece 35 19 upon one end of which are upset two pieces 19^a forming what might be termed a tongue. This tongue fits within the D section of the tension bar tightly, so as to fasten the piece 40 19 very firmly thereto. Upon the other end 45 of the back piece 19, the metal is bent so as to form a boxlike section 20, closed upon its back, ends, and sides but open toward the tension bar. The shape of this box section is 50 such as to allow it to slide within the guideway while conforming very closely thereto, and its length is such as to maintain a fixed angular relationship between the guide and the tension bar as will be understood.

Within the section 20 I place a spring 21, 55 the purpose of which is to bear against the side of the guideway 6 to cause the portion 20 to bind therein sufficiently so that my tension bar may be held against the tension of the spring operating upon the screen in any 60 desired position along the guideways.

In operation the screen cloth lies in the 65 guides and extends beyond the tension bar proper, and in order to minimize wear in the slot of the guides, I prefer to protect the lower edges of the cloth by thin sheet metal

members 22, which may conveniently be of thin sheet brass or copper, and which lie along the back of the part 19 as shown in Figure 6 and are held thereto by a rivet 23.

In this specification I have described a specific embodiment of my invention but various modifications therein are possible to one skilled in the art without departing from the spirit of my invention.

Having thus described my invention, what 75 I claim as new and desire to secure by Letters Patent, is:—

1. In a controlling mechanism for roll screens a tension bar formed of sheet metal bent upon itself to form a tubular section 80 and a channel for a screen fastening, screen fastening means within said channel and means at the end of said tension bar to control the movement of the same along guideways comprising a metallic member operating in said guideways and a spring on said metallic member bearing against said guideways.

2. In a controlling mechanism for rolled closures, a tension bar comprising a sheet of 90 metal bent upon itself to form a tubular section, and a sheet metal member with a tongue adapted to enter said tubular section, a narrow portion adapted to pass through a slot in a guide, and an enlarged section adapted 95 to ride in a guideway lying beyond said slot and a spring mounted on said enlarged section to engage said guideway.

3. In a controlling mechanism for rolled closures, a tension bar comprising a sheet 100 of metal bent upon itself to form a tubular section, and a channel for the attachment of said rolled closure, a fastening means for said rolled closure in said channel, means attached to the end of said tension bar comprising a flat portion adapted to enter a slot in a guide, and an enlarged portion adapted 105 to ride within the guide, a spring mounted within said enlarged portion and bearing against said guideway.

4. In a controlling mechanism for rolled closures, a tension bar comprising a single piece of sheet metal bent upon itself to form a tubular section and a channel for the attachment of said rolled closure, a separate 115 member for controlling the movement of said tension bar along a guide comprising sheet metal bent to form a member for attachment to said tubular section, a flat portion for passing through a slot and an enlarged portion 120 of box shape and substantial length adapted to ride within a guideway, a spring mounted in said box section and adapted to press against the edge of said guideway, a spline for holding the end of said rolled 125 closure in said channel.

5. In a controlling mechanism for rolled screens, a tension bar comprising a body portion and a channel portion for the attachment of the screen cloth, and a metallic piece 130

on either end of said tension bar with a portion to engage said bar, a flat portion to pass through a slot in a guide, and a bearing portion of substantial length and a shape to engage snugly and slidably within said guide channel, said bearing portion being recessed and a spring mounted in said recess and projecting therefrom to engage the wall of a guide channel.

6. In a controlling mechanism for roll closures, a bar to be guided in its movements, a metallic piece on the end thereof with a portion to engage said bar, a flat portion to pass through a slot in a guide and a bearing portion of substantial length and shaped to engage slidably within a channel in said guide, said bearing portion having a spring at least in part projecting from the surface thereof to engage a wall of said guide channel.

7. In a controlling mechanism for roll closures, a tension bar, and means attached to the end of said tension bar to guide it in its movements along a guide, said means comprising a flat portion adapted to enter a slot in said guide and an enlarged portion adapted to ride within the guide, and a spring mounted upon said enlarged portion and bearing against said guideway.
